BOTTLE SEAL

Cornelius J. Desmond, New York, N. Y., assignor
of forty-nine per cent to Doris M. Sullivan, New
York, N. Y.

Application August 23, 1934, Serial No. 741,054

12 Claims. (Cl. 215—21)

My present invention relates to seals for bottles, flasks and the like and more particularly to a seal in the neck of the bottle making it impossible to refill the bottle or container on which 5 my invention is used without destroying some portion of the device which can be seen but not replaced and thereby notifying the purchaser that deception is being practiced.

My device makes it impossible for a bar tender 10 to refill an old bottle or a bottle partly emptied with any liquid such as an inferior brand of liquor. It is also impossible to drain the bottle and refill with inferior liquids and then sell it for the original brand without giving notice to 15 the purchaser.

The principal object therefore is an improved seal for bottles, flasks and similar containers;

Another object is a seal for a container which when once used is destroyed and cannot be replaced again without destroying the container;

Another object is a seal for containers which if used other than intended by the producer of the goods will indicate in a visible manner that a fraud is being practiced upon the purchaser;

Other objects and novel features comprising the construction and operation of my device will appear as the description of the same progresses.

Referring to the drawing illustrating the preferred embodiment of my invention;

Fig. 1 is a side elevation of a bottle to which my invention has been applied;

Fig. 2 is a central vertical cross-section taken on the line 2—2 of Fig. 1;

Fig. 3 is a cross-section similar to Fig. 2 but 35 showing the seal opened;

Fig. 4 is another cross-section taken on the line 4—4 of Fig. 2 particularly showing the ball seat in the upper part of the neck, and

Fig. 5 is a plan view of the inner extension neck 40 after the top cover has been removed.

Referring more in detail to the drawing, 10 indicates a bottle or similar container. In the drawing I have shown the bottle 10 as a separate container which is provided with a grooved 45 split ring 11 adapted to fit around the neck of the bottle 10. Over the neck of the bottle 10 and ring 11 I have placed a glass shell 12 having a groove provided at the bottom inner surface adjacent the groove of the ring 11 and adapted 50 to receive a round split wire locking ring partially engaging in the groove in the casing 12 and partially in the groove of the split ring 11 thereby locking the shell 12 securely to the bottle neck such that it cannot be removed once 55 having been put in place.

I wish to point out at this time that I may construct the bottle 10 and the casing or shell 12 in one piece if it is desired to do so.

At a point midway between the top and bottom of the casing 12 is another groove 13 similar to the bottom groove which is adapted to receive another split wire ring 14 carried in the groove 15 of the extension sleeve 16 such that when the sleeve is pulled up as in Fig. 3 the ring 14 locks in the groove 13 and cannot be dislodged 10 without breaking the casing 12 or the extension neck 16.

The extension neck 16 may be made of any suitable material the bottom end being shouldered at 17 and having an extension end 18 extending 15 down into the neck of the bottle 10 as shown in Figs. 2 and 3. The extension end 18 is further provided with a central tubular opening 19 which extends the entire length of the extension neck 16 to a point below the top terminating in a ball 20 seat 20 which is adapted to receive a ball 21. The top of the extension neck 16 is further provided with a central threaded portion 22 adapted to receive a screw member 23 which when in a closed position bears against the ball 21 and holds 25 it firmly in a seated position binding the cap 24 tightly over the openings 25 through which the liquid is poured.

It will be noted that I have provided a space 26 between the extension neck 16 and the inner side 30 wall of the casing 18. Also I have provided a chamber 27 between the tubular opening 19 and the wall 28 of the extension neck 16, an outlet opening 29 connecting the chamber 27 with the space 26. Connecting also with the chamber 27 35 are openings 30 around the seat 20. Located above the space 26 and in the same plane is another space the two spaces being separated from each other by an annular rib 31. In the upper space I have provided a manufacturer's stamp or 40 similar device preferably composed of some kind of paper and which I have indicated at 32. Around the surface of the extension neck exposed to the space 26 I have provided printed matter 45 with the word "Bonded" or some similar lettering chemically treated such that coming in contact with any liquid discoloration will take place causing an unsightly condition or positively bringing out in a visible manner some such word as Fraudulent. The manufacturer's stamp may state on it that if the bottle is being used while the reading is visible that the purchaser should beware of fraud because when properly used and the extension neck 16 is pulled out the manufacturer's 50 55

stamp 32 is rumpled up as shown in Fig. 3 and cannot be read.

In operation, assume that the bottle is full. The cap 24 is removed by unscrewing the screw 23 and the neck 16 is drawn out destroying the manufacturer's stamp. The contents are poured out through the tube 19 and openings 25. If the bottle is refilled the refill liquid will go into the chamber 27 and pass out into the space 26 discoloring the printed matter around that section and cannot get down into the bottle 18.

Having thus described my invention what I claim as new is:

1. A seal for containers comprising an outer transparent casing, means located at the bottom of said casing to lock said casing to said container, a slidible extension neck located within said casing, means for locking said neck in said casing in an extended position, a central passage located within said neck terminating in a ball seat adjacent the outer end, an annular chamber surrounding a portion of said passage communicating with the exterior surface surrounding said seat and with a space provided between the outer surface of said neck and the inner surface of said casing, an upper space located between said outer surface of said neck and the inner surface of said casing and separated from said first space by means of an annular rib surrounding the outer surface of said neck, a ball and adjustment screw located above said seat adapted to seat said ball tightly.

2. In a seal for bottles and the like, a transparent casing associated with the neck of said bottle, a slidible neck portion located within said casing and from the casing to provide a space for receiving printed matter located between said slidible neck and said casing.

3. A seal for bottles and the like comprising in combination an outer casing adapted to be attached to a bottle neck, a slidible inner neck extension member adapted to be pulled out when used, an inner chamber located in said extension neck adapted to trap fluid when said bottle is refilled, a central chamber adapted to discharge the contents of said bottle, a ball adapted to seat in the end of said central chamber.

4. In a seal for bottles and the like having a transparent casing associated with the neck portion thereof and an extension member slidably disposed in said casing from the casing to provide a space located between said casing and said extension member adapted to receive printed matter, a shouldered portion located on said extension member and in contact with said casing, said shouldered portion adapted to crumple printed matter located in said space when said extension member is drawn upward.

5. A seal for containers comprising a transparent casing associated at the neck portion thereof and an extension member slidably disposed in said casing, a bearing located at the top of said casing adapted to comprise an inner annular shoulder on the inner periphery of said casing and receive said extension member therein, a space located between said casing and said extension member adapted to receive printed matter, a shouldered portion located on said extension member and in contact with said casing, said shouldered portion adapted to crumple printed matter located in said space against said bearing shoulder when said extension member is drawn upwards.

6. A seal for bottles and the like comprising in combination a casing member attached to the neck

of a bottle, an extension member located in said casing, an inner chamber located in said extension member adapted to trap fluid when said bottle is re-filled, a central chamber adapted to discharge the contents of said bottle, a ball adapted to seat in the end of said central chamber, a space located between said casing and extension member adapted to receive printed matter, a shouldered portion located on said extension member, said shouldered portion adapted to crumple the printed matter when the extension member is raised upwards.

7. A seal for containers comprising in combination a casing member solidly fixed to said container at its neck portion, an extension member slidably disposed in said casing, a ball and cap detachably secured at the top of said extension member and located on a seating therein, an annular internal chamber located in said extension member, openings in said seating connecting with said annular chamber, a space located between said extension member and said casing for receiving chemically sensitive matter, an angularly disposed inlet opening connecting said internal chamber with the said space, said seating openings, internal chamber, and inlet opening adapted to conduct liquid to the chemically sensitive matter in said space when the container is refilled.

8. A seal for containers comprising in combination a casing member solidly fixed to said container at its neck portion, an extension member slidably disposed in said casing, a ball and cap detachably secured at the top of said extension member and located on a seating therein, an annular internal chamber located in said extension member, openings in said seating connecting with said annular chamber, a space located between said extension member and said casing for receiving chemically sensitive matter, an angularly disposed inlet opening connecting said internal chamber with the said space, said seating openings, internal chamber, and inlet opening adapted to conduct liquid to the chemically sensitive matter in said space when the container is re-filled, an annular shoulder comprising a portion of said extension member slidably engaging the inner periphery of said casing and dividing the said space into upper and lower chambers, said upper chamber adapted to receive printed matter therein and said shoulder member adapted to crumple said printed matter when said extension member is raised upwards.

9. A seal for containers comprising a transparent casing associated at the neck portion thereof and an extension member slidably disposed in said casing and from said casing to provide a space for receiving printed matter, a bearing located at the top of said casing adapted to comprise an inner annular shoulder on the inner periphery of said casing and receive said extension member therein, a shouldered portion located on said extension member and in contact with said casing, said shouldered portion adapted to crumple printed matter located in said space against said bearing shoulder when said extension member is drawn upwards.

10. A seal for bottles and the like comprising in combination a casing member attached to the neck of a bottle, an extension member located in said casing and from the casing to provide a space for receiving printed matter, an inner chamber located in said extension member adapted to trap fluid when said bottle is re-filled, a central chamber adapted to discharge the contents of said

bottle, a ball adapted to seat in the end of said central chamber, a shouldered portion located on said extension member, said shouldered portion adapted to crumple the printed matter when the extension member is raised upwards.

5 11. A seal for containers comprising in combination a casing member solidly fixed to said container at its neck portion, an extension member slidably disposed in said casing and from the 10 casing to provide a space for receiving chemically sensitive matter, a ball and cap detachably secured at the top of said extension member and located on a seating therein, an annular internal chamber recessed in said extension member, openings 15 in said seating connecting with said annular chamber, an angularly disposed inlet opening connecting with the said space the internal chamber, said seating openings, internal chamber, and inlet opening adapted to conduct liquid to the 20 chemically sensitive matter in said space when an attempt to re-fill the container is made.

12. A seal for containers comprising in combination a casing member solidly fixed to said

container at its neck portion, an extension member slidably disposed in said casing and from said casing to provide a space, a ball and cap detachably secured at the top of said extension member and located on a seating therein, an annular internal chamber located in said extension member, openings in said seating connecting with said chamber, an angularly disposed inlet opening connecting said internal chamber with the said space, said seating openings, internal chamber, and inlet 10 opening adapted to conduct liquid to chemically sensitive matter disposed in said space when an attempt to re-fill said container is made, an annular shoulder comprising a portion of said extension member slidably engaging the inner periphery of said casing and dividing the said space into upper and lower chambers, said upper chamber adapted to receive printed matter therein and said shoulder adapted to crumple said printed matter when said extension member is raised upwards.
